FIG. 3.

Inventor
Hubert Arnold
by J. Weston Haugh & Co
Attest.

UNITED STATES PATENT OFFICE.

HUBERT ARNOLD, OF CALGARY, ALBERTA, CANADA.

MERCHANTISE CARRIER.

Application filed January 2, 1926. Serial No. 78,889.

My invention relates to improvements in merchandise carriers, and the object of the invention is to devise a simple device whereby packages containing fragile articles may be so supported that there will be no danger of breaking such articles during their transit, and it consists essentially of the arrangement and construction of parts as herein-after more particularly explained.

10 Fig. 1 is a perspective view of my device.

Fig. 2 is a similar view to Figure 1 showing my device folded in the position it assumes when not in use.

15 Fig. 3 is a cross sectional view through Figure 1.

Fig. 4 is a cross sectional view through Figure 2.

20 Fig. 5 is a cross sectional view on line 5—5 Figure 3.

In the drawings like characters of reference indicate corresponding parts in each figure.

1 and 2 are longitudinal bars, and 3 and 4 25 transverse bars, the bars 1, 2, 3 and 4 forming a rectangular main frame, and the ends of the bars 3 and 4 projecting beyond the longitudinal bars 1 and 2 for a purpose which will hereinafter appear.

30 5 and 6 are bail members forming jaws which are pivotally mounted at their lower ends on bolts 7 and 8 carried by the outwardly projecting ends of the transverse members 3 and 4 of the main frame.

35 9 and 10 are bolt rods extending transversely of the main frame through the longitudinal bars 1 and 2 thereof.

40 11 is a substantially X-shaped plate extending between the side bars 1 and 2 centrally of the main frame.

45 12 and 13 are orifices formed in the plate 11, the orifice 12 being on one side of the centre of such plate and the orifice 13 upon the opposite side of the centre of such plate.

14 is a channel piece which is secured to the lower face of the plate 11.

15 and 16 are pivoted dogs carried by cross pins 17 and 18 extending transversely of the channel piece 14.

50 19 is a compression spring extending between the lower ends of the pivoted dogs

15 and 16 tending to force their upper ends towards each other. The dogs 15 and 16 are provided with opposing notches 20 and 21 engaging the inner ends of the orifices 12 and 13 and opposing notches 22 and 23 adapted to engage the bails 5 and 6 when swung down into the horizontal position shown in Figure 4. The upper ends of the dogs 15 and 16 are provided with inclined faces 22^x and 23^x with which the bails engage as they are swung downward so as to spread the dogs apart against the pressure of the spring 19 and permit the bails to enter the recesses 22 and 23 in the position clearly indicated in Figure 4.

24 is a U-shaped lever swung upon the cross rod 9, the arms of the lever being of flat bar form bearing directly against the inner face of the bars 1 and 2. The outer ends of the arms are turned horizontally so as to rest flat upon the transverse bars 3 and 4 as indicated at 24^x and 24^y. When the lever 24 is swung up towards a vertical position they serve to hold the bails 5 and 6 in their spread apart position for a purpose which will hereinafter appear.

25 and 26 are bracket members each provided with a central orifice 27 and at their upper edges with hooked portions 28 and 29 80 adapted to extend over the upper edge of the members 5 and 6 as clearly indicated in Figure 1. The lower portion of each bracket 25 forming the lower wall of the orifice 27 is offset inward as indicated at 30. 85

31 is a rectangular frame forming a cradle support for the package of merchandise. Each bracket 25 is provided with outwardly extending downwardly inclined lug portions 32 and 33 connected by tension springs 34 and 35 to the corners of the frame 31.

36 is a cross bar extending transversely and centrally of the frame 31 and provided at its outer ends with outwardly flaring 95 portions 37 and 38 which are secured to the longitudinal bars of the frame 31.

39 is an orifice formed in the centre of the bar 36 through which the pivoted dogs 15 and 16 extend when the parts are in the collapsed position shown in Figures 2 and 4.

40 are brackets secured to the longitudinal

members of the frame 31 between the portions 37 and 38 of the cross bar 36.

41 are steel grips provided with teeth 42 and 43 at their upper ends and teeth 44 and 45 adjacent their upper ends. The lower end of the grips 41 are swung upon hinge pins 46 carried by the hinge brackets 40.

47 is a U-shaped lever swung upon the transverse rod 10. When the arms of the lever 47 are swung upward they extend to

10 the outside of the members 5 and 6 and prevent any danger of the load from toppling either to one side or the other during transit.

47* is a spring catch preventing the arms 15 of the lever 47 from swinging inward when engaging such arms, yet permitting the arms to swing inwardly to take a position to the outside of the bail members when the catch is swung out of engagement therewith. The

20 arms of the lever 24 when swung upward keep the bail members spread to permit of the ready insertion or removal of the load. When in transit these arms are placed horizontally.

25 When I desire to use my device, the parts are arranged as shown in Figure 1 and the container containing the articles to be carried is placed upon the cradle support 31 and the weight of such load portions expands 30 the springs 34 and 35, such pull tending to draw in the members 5 and 6 towards the load and thereby force the teeth 42, 43 and 44, 45 into the sides of the load so as to securely grip it and hold it in place, and at the 35 same time so supporting the load that it is resiliently carried upon the support 31, the gripping members 41 rising and falling therewith according to the vibration to which the merchandise is subjected in transit.

40 It will thus be seen that the package or container holding the fragile articles is firmly held definitely in place and yet will be resiliently supported so that any jar or shock is absorbed by the springs 34 and 35 45 as it tends to be transferred to such container.

When the device is not in use it may be readily collapsed in the position shown in Figures 2 and 4 by first removing the 50 brackets 25 and 26 out of engagement with the members 5 and 6, placing them upon the frame 31 and placing such frame 31 upon the main frame formed by the members 1, 2, 3 and 4. It will of course be understood 55 that during this operation the levers 47 and 24 are placed in a horizontal position. After the frame 31 is placed upon the main frame as above described the bail members 5 and 6 are swung downward over the frame 31 so 60 as to engage the pivoted dogs 15 and 16 in the manner above described, such dogs passing through the orifice 39 to permit of their engagement with such members 5 and 6. When the package or container is in the carrying position in the device, such mer-

chandise carrier may be raised and moved to any desired position by means of the handle lugs 47°.

From this description it will be seen that I have devised a very simple device whereby 70 containers or packages holding fragile articles may be supported in safety during transit by means which are simple and may be compactly folded for storage when not in use.

What I claim as my invention is:

1. A merchandise carrier comprising a rectangular main frame, a bail member 80 swung at each side of the main frame, a cradle support resiliently mounted between the bail members, and gripping jaws carried by the cradle support and adapted to be forced into contact with the article carried by the cradle support by its weight upon such support.

2. A merchandise carrier comprising a main frame, bail members pivotally mounted at each side of the main frame, a cradle support resiliently carried between the bail members and tending to draw such bail 90 members inward by its weight and the load carried thereby, and tooth grips carried by the cradle support and adapted to have their tooth ends forced inward against the article carried by the cradle support by its weight 95 thereon and the inward pull upon the bail members produced thereby.

3. A merchandise carrier comprising a rectangular main frame, a bail member 100 pivotally mounted at each side of the main frame, a U-shaped lever pivotally carried by the main frame, and having arms adapted to extend upward between the bail members to space them apart, a cradle support resiliently mounted between the bail members, and toothed grips connected to the cradle support adapted to have their tooth ends forced inwardly against the cradle load by the yielding action of the cradle support and the inward pull upon the bail members.

4. A merchandise carrier comprising a rectangular main frame, bail members carried at each side of the main frame, a rectangular frame forming a cradle support, brackets hooked over the central portion of the bail members and having a central orifice, springs connecting each end of the bracket with a corresponding outer corner of the cradle frame, and a grip hingedly connected to each side of the cradle support and extending upward through the orifices of the brackets directly to the inside of the bail members.

5. A merchandise carrier comprising a rectangular main frame, a cross plate extending centrally transversely of the main frame, opposing spring pressed gripping dogs carried by the plate, bail members 115 swung at each side of the main frame and adapted when swung down to a horizontal

position to be engaged by the aforesaid dogs, a cradle support comprising a rectangular frame, brackets hooked over the bail members at the opposite side of the carrier, tension springs connecting the corners of the cradle support with the bracket, toothed grips pivotally connected to the cradle sup-

port and extending upward at the inside of the bail members and slidably longitudinally in the brackets, and a U-shaped lever ¹⁰ adapted to be swung up on the outside of the bail members to prevent lateral sway.

HUBERT ARNOLD.
